UNITED STATES PATENT OFFICE

93,918

DESIGN FOR AN EMBROIDERED TEXTILE FABRIC

Moses F. Gantz, Yonkers, N. Y.

Application April 18, 1933, Serial No. 47,825

Term of patent 3½ years

To all whom it may concern:

Be it known that I, Moses F. Gantz, a citizen of the United States, residing at Yonkers, in the county of Westchester and State of New York, have invented a new, original, and ornamental Design for an Embroidered Textile Fabric, of which the following is a specification, reference being had to the accompanying drawing, forming part thereof:

Figure 1 is a plan view of an embroidered textile fabric showing my new design, while Figure 2 is a plan view of the embroidered textile fabric

showing a section of the design drawn to a larger scale than is disclosed in Figure 1.

The section of the design shown in Figure 2 is drawn to approximately twice the size of the design as shown in Figure 1, the latter being a reproduction of the actual fabric.

I claim:

The ornamental design for an embroidered textile fabric as shown and described.

In testimony whereof, I hereunto affix my signature.

MOSES F. GANTZ.
